UNITED STATES PATENT OFFICE.

GEORGE E. BERNECKER, OF MILWAUKEE, WISCONSIN, ASSIGNOR, BY MESNE ASSIGNMENTS, TO RECORD NEEDLE & MANUFACTURING CO., OF MILWAUKEE, WISCONSIN.

LIGHTING ATTACHMENT FOR SOUND-REPRODUCING MACHINES.

1,319,690.

Specification of Letters Patent.

Patented Oct. 28, 1919.

Application filed October 18, 1917. Serial No. 197,282.

To all whom it may concern:

Be it known that I, GEORGE E. BERNECKER, a citizen of the United States, residing at Milwaukee, in the county of Milwaukee and 5 State of Wisconsin, have invented new and useful Improvements in Lighting Attachments for Sound-Reproducing Machines, of which the following is a specification.

This invention relates to lighting attachments 10 for sound reproducing machines.

One of the objects of the invention is to provide an improved lighting attachment which may be used with any type of sound reproducing machine.

15 Another object is to provide a lighting attachment which may be readily applied, easily operated, applies light where and when needed and which is of improved appearance.

20 Another object is to provide improved switching means for opening and closing the circuit of the light.

Other objects will appear from the following specification and claims.

25 In the drawings Figure 1 is a view of the complete lighting attachment mounted on the table of a sound reproducing machine.

Fig. 2 is a perspective of the complete lighting attachment.

30 Fig. 3 is a vertical section through the center of the attachment.

Fig. 4 is a disassembled perspective showing the relation and method of assembling the parts.

35 Fig. 5 is a bottom plan of the cap of the attachment, and

Figs. 6 and 7 are views of the insulators used.

The attachment comprises a tubular stand- 40 ard 5 having an enlarged hollow base 6 and an enlarged barrel 7 at its upper end. The base 6 is provided with openings 8 through which screws may be passed to secure the attachment to the table of the sound repro- 45 ducing machine.

The barrel 7 is provided with an opening 10 in its front wall through which the electric light can project as hereinafter described. The rear wall of the barrel 7 has 50 a cut-away portion or notch 11 the lower edge of which is inclined as shown at 12. An insulating sleeve 15 encircles the outer wall of barrel 7. This sleeve is provided with an opening 16 registering with opening 10, and a notch or cut-away portion 17

registering with the cut-away portion 11 of barrel 7. This sleeve is made from punched strips of paper such as shown in Fig. 6, the round opening 16 being formed by the placing together of the two ends of a punched paper strip so that the semi-circular cut in each is opposite and complementary of each other. The upper part of the attachment comprises a cap 20 adapted to be slipped over the barrel 7 and insulator 15 and close 60 the upper end of the standard. The cap is provided in its forward face with a tubular sleeve 21 into which may be forced the lamp socket and a light projector 22. The socket 22 is adapted to be readily inserted and removed from the sleeve 21 and when in position the lamp 23 and lamp terminal 24 do not touch the wall or opening 10 in barrel 7. 70

The cap 20 has pivoted to the center of its top a switch arm 25. This switch arm projects through a slot 26 in the rear wall of the cap where it may be manipulated by the fingers. A paper insulating washer 27 lies in the top of the cap between its top wall and arm 25 and prevents the upper edge of barrel 7 from making contact with the upper wall of the cap. The leads 30 and 31, from a source of current such as a dry battery 32, pass through a notch 33 in the base 6. Lead 31 is secured by a suitable terminal 85 35 to the base 6, while lead 30 is secured to the inner terminal of the lamp.

In assembling the attachment the paper sleeve 15 is wrapped about barrel 7. Cap 20 is then forced down over the sleeve 15 with 90 its switch arm 25 coming within the cut-away portion 11. The socket 22 is then forced into the sleeve 21, the lead 30 having previously been secured to the lamp terminal. When thus assembled as long as switch 95 arm 25 is in the deeper portion of notch 11 the circuit of the lamp is open. When, however, the switch arm 25 is turned to the left so that it rides up on the inclined edge 12 it will wedge between this edge and the upper edge of the slot 26 and a circuit will 100 then be completed for the lamp as follows: from lead 30 through the lamp, through socket 22 and sleeve 21 to the cap 20, then from the upper edge of slot 26 through the 105 switch arm 25 to the inclined edge 12 of notch 11, then through the barrel 7 and standard 5 to the terminal 35 and then out through the lead 31. When the switch arm 25 is moved into the deeper portion of the 110

notch 11 this circuit is broken as the current cannot then pass from the cap 20 to the barrel 7.

This attachment may be applied to any of 5 the well known types of sound reproducing machines, and the light will be projected upon the needle and record. The light may be readily turned off and on by slight movement of the switch arm 25.

10 What I claim is:

1. A lighting attachment for sound reproducing machines, comprising a hollow, upright standard having a base adapted to rest upon the table top, a cap fitting over 15 and closing the upper end of said standard, but insulated therefrom, light projecting means supported by and electrically connected to said cap for illuminating a portion of the machine record, said standard and 20 light projecting means adapted to be electrically connected with the opposite terminals of a source of current, and a switch for opening and closing the circuit between said cap and said standard.
- 25 2. An attachment for lighting the records of sound reproducing machines having an electric light arranged to project light in only one direction, an upright tubular standard supporting the light in position above 30 and to the side of the record, and having a cut-away portion at its upper end, a cap closing the upper end of the standard, insulating means between the cap and standard, circuit connections inclosed by the 35 standard one secured to the light and one secured to said standard, and a switch arm pivoted to said cap and adapted to engage the standard or move in the cut-away portion to make and break circuit for said light.
- 40 3. A switch comprising a tubular body having an irregular cut-away portion a cap fitting over and closing one end of said body, insulating means between said body and cap, and having a cut-away portion 45 corresponding to the cut-away portion of said body, and an arm pivoted to said cap and movable within the cut-away portions of said body and said means and co-operating with said body to make and break contact therewith.
- 50 4. A lighting attachment for sound reproducing machines comprising an electric light, a tubular standard supporting the light in projecting position, a cap covering 55 the upper end of said standard, said cap

having a slot in its wall, a switch arm pivoted to the top of the cap and projecting through said slot and said standard having a cut-away portion in which said switch arm may move, said cut-away portion having an inclined lower edge so that when the switch arm is moved in one direction it will establish an electrical connection between the cap and standard, and when moved in the other direction it will break such connection. 60

5. A lighting attachment for sound reproducing machines, comprising a vertical standard adapted to rest on the table of the machine, means for projecting light upon the record, a cap fitting over the upper end of said standard and normally insulated therefrom, a switch for completing an electric circuit between the standard and the cap and means whereby the attachment may 75 be electrically connected to a source of current which is separate from said attachment.

6. A lighting attachment for sound reproducing machines, comprising a standard adapted to rest on the table of the machine, means for projecting light upon the record, a cap for said standard and normally insulated therefrom, a switch member movable to and adapted to remain in 80 either of two positions, means whereby said switch member in one of its positions will establish an electrical connection between the standard and the cap, said connection being broken when the switch member is in 85 its other position and means whereby the attachment may be electrically connected to a source of current which is separate from the attachment. 90

7. A lighting attachment for sound reproducing machines, comprising a vertical, tubular standard adapted to rest on the table of the machine, means for projecting light upon the record, a cap fitting over the upper end of said standard and normally 100 insulated therefrom, a switch lever pivoted to the top of said cap and projecting radially from the cap and means whereby said switch arm in one position will establish an electrical connection between the standard 105 and the cap, said connection being broken in another position of said switch arm.

In witness whereof, I have hereunto subscribed my name.

GEORGE E. BERNECKER.
